UNITED STATES PATENT OFFICE.

JAMES H. READER, OF KANNAPOLIS, NORTH CAROLINA.

COMBINED ROLL-HOLDER, CUTTER, AND TWINE-HOLDER.

1,340,132.

Specification of Letters Patent.

Patented May 11, 1920.

Application filed July 17, 1915, Serial No. 40,469. Renewed March 30, 1920. Serial No. 370,036.

To all whom it may concern:

Be it known that I, JAMES H. READER, a citizen of the United States, residing at Kannapolis, in the county of Cabarrus and State of North Carolina, have invented certain new and useful Improvements in Combined Roll-Holders, Cutters, and Twine-Holders; and I do hereby declare the following to be a full, clear, and exact description 10 of the invention, such as will enable others skilled in the art to which it appertains to make and use the same.

The primary object of this invention is to admit of the holders for paper rolls and twine being so disposed with relation to a counter in a store that they will not take up room on the counter, will not interfere with the service over the counter, and will be so disposed that the paper and cord can be conveniently reached by the person desiring access to the same.

Another object of the invention is to combine a paper roll holder and twine holder, that can be manufactured cheaply and readily installed in a store.

Other objects will appear and be further understood from that embodiment of my invention of which the following is a specification, reference being had to the accompanying drawings forming a part thereof, in which:

Figure 1 is a side elevation of the combined paper roll holder and twine holder in applied position.

Fig. 2 is an end view thereof.

Referring to the drawings, the paper roll holder and twine holder is designated, as an entirety, by the letter A and includes a pair of vertically disposed depending supports 40 arranged in spaced relation and each of which is formed of an upper tubular section 1 having its upper end received by an annular flanged cap 2 adapted to have detachable connection with the ceiling, by means of the fastening element 3, as shown in the drawing, and a lower tubular section 4, the said lower section 4 having connection with the upper section 1 by means of a T-joint 5. The lower ends of the lower sections 4—4 50 have mounted thereon T joints 6—6.

Positioned at the lower ends of the lower sections 4—4 of the vertically disposed supports, and on opposite sides of said supports and extending at right angles to the lower sections are tubular arms 7 and 8, each of the arms having one end received by the

adjacent T joint and having its opposite end received by one end of a U coupling 9, the opposite ends of the U-shaped couplings carried by the supporting arms of one of the 60 vertical supports being extended in the direction of the U couplings carried by the tubular arms on the opposite vertical support. The last-mentioned ends of U couplings are provided with cut-out portions 10. The cut-out portions 10 on opposing couplings are adapted to receive and form bearings for the opposite ends of rollers 11—11, which rollers extend through and support rolls of paper, designated 12 and 13.

Interposed between the vertically depending supports and extending at right angles thereto is a bar formed of a plurality of tubular sections 14, 15, 16 and 17. These sections are connected, to form a unitary 75 structure, by means of the heads of T joints 18, 19 and 20, as shown in Fig. 1, and the extreme sections 14 and 17 have connection with the stems of the T joints 5—5 carried by the adjacent vertical depending supports. 80

The stems of the T joints or couplings 18, 19 and 20 extend upwardly, as shown in Fig. 1, and the said stems of the said T joint couplings receive supporting stems 23, 24, and 25 carried by substantially globular 85 shaped twine holders 26, 27 and 28, each of the said twine holders comprising companion semispherical sections, the uppermost section of each twine holder being removable and perforated for the passage of 90 twine, designated by the letter C, therethrough and the lowermost sections of the twine holders having secured thereto the lower ends of vertically disposed guides 29, 30 and 31, the said guides having their upper ends disposed above the respective twine 95 holders and each having its upper end provided with an eye 32 through which passes the twine, as shown in Fig. 1 of the drawing.

Each of the upper sections 1 of the vertically disposed supports, is provided with a guide 33 which is formed of a piece of wire coiled at a point adjacent one end to provide an eye 34 for the passage of the twine, and the opposite terminals of the guides 33 105 are bent at right angles to the main body portion of the guides, as shown at 35 and 36, and serve to hold the said guides spaced from the adjacent section 1 and are secured to the said sections by soldering or in any 110 other suitable manner. The guides 33 have slidably mounted thereon weights 37, and

these weights 37 have the twine C passing therethrough and said weights are adapted when the twine is being pulled upon the holders and through the guides to have vertical sliding movement on the guide 33, and when the twine is released said weights will descend and place the twine under tension.

Each of the sections 14 and 17 has associated therewith a pair of swinging arcuate shaped arms 38 and 39, the arms forming each pair extending in opposite directions and downwardly toward the opposite rolls of paper 12 and 13, and the respective arms have connection with the sections 14 and 17 by eyes 39', formed by looping the upper terminals of the arms and which eyes loosely receive the respective sections. The lower ends of the arms 38 and the lower ends of the arms 39 carry transversely extending strips 41 and 42, each strip having a beveled edge 43 and the rear surface of the strips 41 and 42 carry metallic strips 44, which project below the lower longitudinal edges of the strips 41 and 42 and rest upon the adjacent rolls of paper 12 and 13, and serve to provide guide strips by means of which the paper can be torn evenly from the roll.

From the foregoing description taken in connection with the accompanying drawings, it will be seen that a combined paper

holder and twine holder will be provided and can be so positioned with respect to a counter in a store that it will not take up room on the counter and will not interfere with the service over the counter, and will be so disposed that the paper and twine can be conveniently reached by a person desiring to have access to the same.

Having thus described my invention what I claim as new is:

A roll holder comprising a pair of vertically disposed supporting elements, horizontally disposed arms located at the lower ends of the supporting elements and secured thereto and extending at right angles to the supporting elements, roll-supporting elements journaled in the opposite ends of the respective arms, a bar interposed between the vertically disposed supporting elements and disposed above the planes of the arms and the roll supporting elements, roll-engaging strips, and arcuate shaped arms pivotally carried by the bar and having connection with the roll-engaging strips.

In testimony whereof I affix my signature in presence of two witnesses.

JAMES H. READER.
